UNITED STATES PATENT OFFICE.

BILL H. Poulos, OF HAUGAN, MONTANA.

ANTICREEPING TIE PLATE.

Application filed December 15, 1922. Serial No. 607,229.

To all whom it may concern:

Be it known that I, BILL H. Poulos, a citizen of the United States, residing at Haugan, in Mineral County and State of Montana, have invented certain new and useful Improvements in Anticreeping Tie Plates, of which the following is a specification.

My present invention relates to improvements in anti-creeping tie plates designed to be used under the rails of railway tracks to prevent longitudinal creeping of the rails, as well as to prevent lateral movement or spreading of the rails, when the latter are subjected to the strains imparted thereto by the weight of passing rolling stock.

The primary object of the invention is the provision of a tie plate which is comparatively inexpensive in cost of production, is simple in construction and durable, and which is provided with locking means for maintaining the rail in proper condition at all times. Due to its simplicity in construction the plate may with facility be installed in position for use beneath the rail and there locked, and subsequently the plate may be maintained in proper position for holding the rail in safe condition. To this end the invention consists in certain novel combinations and arrangements with the plate, which plate extends substantially from edge to edge of the rail base, whereby the plate and locking member or section afford a secure anchor for the rail. In practice a suitable number of the plates are anchored to the ties and the plates are placed at desired intervals throughout the length of the rail.

In the accompanying drawings I have illustrated one complete example of the physical embodiment of my invention wherein the parts are combined and arranged according to the best mode I have thus far devised for the practical application of the principles of my invention.

Figure 1 is a perspective view of a portion of a railway rail and cross ties, showing the utilization therewith of the anti-creeping tie plate of my invention.

Figure 2 is an enlarged, vertical, transverse sectional view through a rail and tie plate.

Figure 3 is a perspective view of the tie plate with its locking member or section in working position.

In order that the utility of the device and the relation of parts may readily be under-

stood I have shown a portion of a standard track rail as 1 with its flanges 2 and 3 forming the base thereof, and the cross ties are designated as 4.

The tie plates 5 are anchored directly on the cross ties and these plates, which are produced in suitable manner, are of standard sizes to correspond with the rail flanges and base, and are installed beneath the rail 65 and on the tie at intervals throughout the length of the rail, to meet existing conditions. The plate is approximately the width of the rail base, extending from edge to edge thereof, and is fashioned with a retaining flange 70 6 to fit over one of the rail flanges as 3, and a lateral extension or spike flange 7 having one or more spike holes 8.

On the under faces of the plates are projecting spurs 9, and it will be apparent that when the plate is slipped under the rail base, as from the right side in Figure 2, these spurs will become embedded in the top face of the tie. By means of spikes driven through the spike holes and into the cross tie 80 and with the aid of the spurs, the tie-plate is securely fastened to the cross tie, and the retaining flange by its engagement with the rail flange 3 holds the rail from spreading.

At the edge of the plate opposite to the retaining flange 6, the plate is fashioned with a longitudinally extending tapered groove 10 in its upper surface, the outer wall of the groove being disposed at a slight angle to the longitudinal axis of the 90 plate, and the inner, undercut wall 11 of the groove being disposed parallel with the longitudinal axis of the plate. At the edge of the plate a corner rib 10' is thus formed, which tapers in width from end to end, the outer, top edge of the rib being parallel with the longitudinal axis of the plate.

In connection with the tie plate I utilize a locking section 12, located at the side of the rail and adapted to interlock with the 100 plate in engagement with the rail, to maintain the flange 2 of the rail in position. The detachable and adjustable locking section conforms to the shape and size of the tie plate and forms a complementary part 105 thereof. It is provided with spike holes 13 through which the spikes are driven into the tie for holding the section in locked position, and is fashioned with a flange retaining flange 14 complementary to the flange 110 6, to engage over and hold the base flange 2 of the rail.

A locking rib 15, in the shape of a wedge, is provided at the underside of the retaining flange 14, and between the rib and flange 14 a groove 16 is fashioned, said groove extending laterally over the flange. A second groove 15' which extends vertically, is provided in the under portion of the locking section, and the inner face of the rib 15 is beveled as seen at 17.

10 After the tie plate has been installed under the rail with the retaining flange 6 engaged over the rail flange, the locking section may be fitted and adjusted and secured in locked position. In locating the locking 15 section, it may first be held between the ties with the wedge rib 15 alined with the tapered groove 10, and while in this plane the wedge is inserted into the groove. The retaining flange while the section is in this 20 position projects over the edge of the rail flange 2. The section may now be forced or moved along the edge of the rail flange and due to the angular disposition of the outer wall of the groove 10 the vertical wall of 25 the slot 16 of the locking section is caused to frictionally engage the edge of the flange, while the retaining flange 14 is forced over the rail flange 2. In this manner the two rail flanges 2 and 3 are clamped securely 30 between the respective retaining flanges 14 and 6, and with the spikes driven through the several spike holes 8 and 13 and spurs 9 embedded in the cross tie, the rail is firmly

anchored by the tie plate to the cross tie. In the event that the necessity should arise for tightening the locking member, its spikes 35 may be removed, and then the section may be driven longitudinally of the tie plate, causing the section to be brought nearer to the rail for clamping action. In case it is necessary to remove the tie plate, after the spikes have been withdrawn, the locking section may be backed off the tie plate, thus, 40 permitting the plate and locking section to be removed from opposite sides of the rail.

Having thus fully described my invention, what I claim as new and desire to secure by Letters Patent is:—

The combination with a tie plate having a rail retaining flange extending throughout its length, a perforated spike flange and tie-engaging means on its bottom, of a locking section having a rail retaining flange extending over said plate and having its bottom flush with the bottom of the plate and perforated for spikes; said locking section having a wedge shaped bead with a beveled face, and said tie plate having a top groove formed with an undercut wall parallel with the longitudinal axis of the plate and a perpendicular wall disposed at an angle to the longitudinal axis of the tie plate.

In testimony whereof I affix my signature.

B. H. POULOS.
